UNITED STATES PATENT OFFICE.

EDWIN TERRY, OF BROOKLYN, NEW YORK.

DESIGN FOR A WATCH-CHARM.

SPECIFICATION forming part of Design No. 18,356, dated May 29, 1888.

Application filed March 29, 1888. Serial No. 262,876 Term of patent 7 years.

To all whom it may concern:

Be it known that I, EDWIN TERRY, of Brooklyn, in the county of Kings and State of New York, have invented a new and original Design for Watch-Charms, of which the following is a full, clear, and exact specification.

My new design is fully illustrated in the accompanying drawing, to which reference is made.

- 10 The leading feature of the design consists of a ball, A, in imitation of a common base-ball, having the curved line B and diagonal short lines c c on each side of said curved line to imitate the cover and stitching of a base-ball.
- 15 At the top of the ball A appears the column C, surmounted by a ring, D, and circular bead- ing E F. At the juncture of the column C

with the axis of the ball A is the circular molding G. Opposite the column C and in line therewith appears the circular and tapering point H, above which at its juncture with the ball appears the conical and truncated molding J. The column C and point H are in line with the axis of the ball A.

I claim—

25 The design for a watch-charm, substantially as herein shown and described, the same consisting of the ball A, curved line B, diagonal lines c, column C, and point H.

EDWIN TERRY.
